UNITED STATES PATENT OFFICE

HERMANN OBERSCHULTE, OF ESSEN-ON-THE-RUHR, GERMANY

DEVICE FOR USE IN FORMING UNDERCUT SECTIONS OF ROLLED METAL

Application filed June 4, 1927, Serial No. 196,601, and in Germany June 9, 1926.

This invention relates to mills for bending and shaping metal bars or sections and aims to provide an improved device for forming undercut sections of rolled metal.

5 It is very difficult to form or properly shape undercut sections of metal by rolling or bending the same in the rolling mill, and as a rule, very uneven results are obtained. Consequently, the practice of performing the 10 reshaping operation outside the rolling mill by means of guides has been adopted, but in many cases, the guides are inefficient on account of the heavy frictions imposed thereon.

Distinguished from known arrangements, 15 the present invention provides a bending or reshaping device located exteriorly of the rolling mill and consisting of separate rolls acting upon the metal, said rolls being plain or profiled.

20 In the accompanying drawings, two embodiments of the invention are illustrated diagrammatically by way of example and further description of the invention will be made with reference to said drawings 25 wherein:

Figs. 1 and 2 are respectively an elevation and a plan view of one form of the reshaping device; and

30 Figs. 3 and 4 are similar views of another form of the device.

Referring particularly to Figs. 1 and 2, the illustrated device is represented as acting on the ridges a , a of an initially formed or rolled bar or section p so as to bend them 35 to new positions forming a groove in the bar. Said bar is advanced to the rolls r^1 , r^1 by which its said ridges are first forced from the positions a^1 , a^1 to the positions a^2 , a^2 , and as the bar is moved forward, its ridges are 40 next engaged by rolls r^2 , r^2 , which force the same from the intermediate positions a^2 , a^2 to the final positions a^3 , a^3 .

To facilitate the initial gripping of the bar by the rolls, the block or carriage k in 45 which the rolls are mounted is made vertically adjustable to permit raising and lowering (as indicated by the arrow) so as to bring the rolls in gripping contact with the bar.

Instead of the embodiment above described, the rolls may be adjustably mounted

in the block k with their axes on inclined and diverging planes oblique to the advancing bar, as viewed in the direction of rolling.

Figs. 3 and 4 represent such an arrangement of rolls r , r whereby the ridges of the bar are gradually and uninterruptedly pressed over from the positions a^1 , a^1 , to the final positions a^3 , a^3 .

The number and shape (or profile) of the rolls may be varied in accordance with the purpose in view. A plurality of rolls may be arranged in successive pairs, and instead of plain rolls such as shown, rolls of trunconical or profiled surface may be employed to give shape to the ridge-portions a of the bar. In order to still further reduce the friction produced by the passage of the bar through the reshaping device, driven or idling rollers d may advantageously be used in place of a fixed support below the bending rolls as represented, and such rolls may be profiled or made in any other shape to suit working conditions.

Having now fully described my invention, what I claim as new and desire to secure by Letters Patent is:—

1. A device for forming undercut sections of rolled metal comprising a block or carriage supported resistably against lifting force and adapted to vertical adjustment, hardened bending rolls mounted in said block or carriage in successive oppositely inclined pairs along a horizontal path of movement of the bar or section of metal to be rolled so as successively to non-yieldingly apply bending force in opposite directions upon portions thereof in a step-wise reshaping or molding operation, the said rolls being rotatably mounted respectively on axes oblique to said path of movement of the material, and friction-reducing rollers supporting the bar or section of metal moved against the rolls under said block.

2. A device for forming undercut sections of rolled metal comprising a block or carriage supported resistably against lifting force and adapted to vertical adjustment, hardened reshaping rolls mounted in said block or carriage under which a bar or section of metal is moved in a horizontal path

with said rolls non-yieldingly applying bending force upon portions of the latter, the said rolls being rotatably mounted on axes inclined or oblique to said path and arranged in opposing pairs successively closer together with inclination at different angles so as to act on the bar in a step-wise reshaping or molding operation during movement along its path, and friction-reducing rollers supporting the bar in movement under said block; said device being located exteriorly of a rolling mill wherein the material is initially formed.

3. A device for forming undercut sections of rolled metal comprising a block or carriage supported resistively against lifting force and adapted to vertical adjustment, hardened reshaping rolls mounted in said block in successive oppositely inclined pairs along a horizontal path of movement thereunder of the bar or section of metal to be rolled so as successively to non-yieldingly apply bending force in opposite directions upon portions of the bar in a step-wise reshaping or molding operation, the said rolls being rotatably mounted on axes inclined or oblique to the travel path of the material within planes at right angles thereto, and friction reducing rollers supporting the bar in movement under said block; said device being located exteriorly of a rolling mill wherein the material is initially formed.

In testimony whereof I have affixed my signature.

HERMANN OBERSCHULTE.
